UNITED STATES PATENT OFFICE.

OTTO FELIX FEIX, OF GLOVERSVILLE, NEW YORK, ASSIGNOR TO GLOVERSVILLE
ABRADING COMPANY, OF GLOVERSVILLE, NEW YORK, A CORPORATION OF NEW
YORK.

LEATHER-DRESSING MACHINE.

1,241,363.

Specification of Letters Patent. Patented Sept. 25, 1917.

Application filed November 17, 1916. Serial No. 131,881.

To all whom it may concern:

Be it known that I, OTTO F. FEIX, a citizen of the United States, residing at Gloversville, in the county of Fulton and State of New York, have invented a new and useful Leather-Dressing Machine, of which the following is a specification.

This invention has reference to leather dressing machines, and is designed to provide an abrading machine for fine tanned leather, being an improvement upon the leather dressing machine shown and described in my application No. 37,750 filed July 2d, 1915.

The machine of the prior application contained an abrading roller with a carborundum or similar abrading surface, together with feeding rollers arranged to deliver the leather to the abrading roller, and in conjunction with the feeding rollers there is a presser plate for holding the leather against the abrading roller.

In accordance with the present invention there is provided an abrading roller as before, but instead of a presser plate the abrading roller has associated therewith a presser roller which may be rubber covered, and associated with the presser roller are guide rollers constituting idlers and constrained sufficiently toward the presser roller to be actuated by pressure exerted on them through the leather or skin traveling between the presser roller and the guide rollers.

In the prior application the feed rollers are driven directly by gearing interposed between the guide rollers and the abrading roller, the latter being driven by power from any suitable source.

In the structure of the present invention the means for transmitting power from the abrading roller is much simplified in structure and also rendered more flexible by the employment of sprockets and chains, with only so much gearing as is necessary to insure the proper direction of rotation and the proper speed of rotation.

The invention will be best understood from a consideration of the following detailed description, taken in connection with the accompanying drawings forming part of this specification, with the further understanding that while the drawings show a practical form of the invention, the latter is not confined to any strict conformity with

the showing of the drawings, but may be changed and modified so long as such changes and modifications come within the scope of the appended claims.

In the drawings:

Figure 1 is an end elevation of a machine embodying the invention.

Fig. 2 is a vertical front to rear section showing the rollers in end elevation.

Fig. 3 is a front elevation as viewed from the left hand side of Figs. 1 and 2, of the upper or roller containing portion of the machine.

Fig. 4 is a view similar to Fig. 3 but confined to the lower or treadle portion of the machine, with some parts in section.

Referring to the drawings there is shown a supporting frame 1 which may be made of web and flange construction with the parts principally in the form of castings, but these are matters of detail construction and may be varied within wide limits. Furthermore, the frame construction needs no special description.

On top of the frame at opposite sides are guide portions 2 on which there is mounted a carriage having end members 3 capable of sliding lengthwise on the guides, and carrying a top 4 constituting a table facilitating the handling of the skins while being treated. Each end 3 of the carriage is traversed by a stop screw 5 tapped therethrough and having a manipulating wheel 6 in accessible position so as to limit the extent of movement of the carriage in the direction and for a purpose which will hereinafter appear.

On each top member 2 is a rack bar 7 engaged by a pinion 8 on the corresponding end of a rock shaft 9 journaled in and extending through the sides 3 of the carriage. At appropriate points on the shaft 9 are secured offstanding arms 10, each connected at its outer or free end to a link 11 directed downwardly and having a pivotal connection 12 with a treadle 13 in turn pivotally mounted at 14 in appropriate portions of the frame 1. The treadle 13 has a foot-board 15 in convenient position to be pressed upon by the foot of the operator, while the other end of the treadle carries weights 16 in number and size sufficient to overbalance the foot board end of the treadle and to move certain parts by the action of gravity.

Journalized in the side members 3 of the carriage is a shaft 17 carrying a roller 18, which latter, as appears from Fig. 2 of the drawings, is provided with a rubber surface or covering 19.

Mounted upon journal bearings 20 on the side members of the frame 1 is a shaft 21 carrying a carborundum roller 22. This roller may, as shown in the drawings, be provided with a surfacing 23 of carborundum or similar abrasive material, or it may be entirely of carborundum, these being matters which do not in themselves enter into the present invention. The roller 18 is so mounted on the carriage that its rubber surface 19 may be brought into close relation to the abrading roller 22. The particular approach of the roller 18 which, as will hereinafter appear, constitutes a presser roller, to the abrading surface of the roller 22, is determined by the stop screws 5.

Power is applied to the shaft 21 through a pulley 24 by way of a belt 25 or in any other suitable manner.

Journalized in the frame 1 at a low point thereon is a shaft 26 carrying a gear pinion 27 and a sprocket wheel 28. The pinion 27 and sprocket wheel 28 are in the particular showing of the drawings at respectively opposite ends of the shaft 26. Adjacent to the shaft 26 is another shaft 29 journalized in the frame 1, and this shaft carries at one end a gear wheel 30 meshing with the pinion 27 and at the other end carrying a sprocket pinion 31.

Mounted on the shaft 21 is a sprocket pinion 32 and mounted on the shaft 17 is a sprocket wheel 33.

Connecting the pinion 32 with the gear wheel 28 is a sprocket chain 34 and connecting the sprocket pinion 31 with the sprocket wheel 33 is a sprocket chain 35.

Power applied through the belt 25 causes a rotative movement of the abrading roller 22, and motion is transmitted from the shaft 21 of the roller 22 through the sprocket chain 34 to the shaft 26, and the latter transmits motion by way of the gears 27 and 30 to the shaft 29, which in turn transmits motion to the roller 18 by way of the sprocket pinion 31 and sprocket wheel 33. The sprocket pinions and wheels and the gear pinion and gear wheel are so proportioned that a comparatively high speed of rotation may be imparted to the abrading roller, and at the same time the presser roller 18 may be rotated at a comparatively slow rate. As an example the abrading roller may rotate from eight hundred to a thousand revolutions per minute, while the presser roller has a peripheral speed of about fifteen feet per minute.

Associated with the presser roller 33 are other rollers 36, 37, respectively. These two rollers 36 and 37 have rubber coverings or

envelops 38, and are carried by respective shafts 39 and 40. The roller 36 has its shaft 39 carried in bearing blocks 41 mounted to slide in guides 42 in one end of bracket arm 43 has a foot portion 44 provided with on opposite sides thereof. Each bracket arm 43 has a foot portion 44 provided with a longitudinal slot 45 traversed by screws or bolts 46 threaded into the corresponding portion of the frame 1, so as to support the bracket arm 43 in different positions of adjustment, the bracket arm being held fixedly in adjusted positions by tightening the screws 46.

The roller 37 carried by a shaft 40 is journaled at the ends in bracket arms 48 having foot portions 49 with longitudinally extended slots 50 traversed by screws or bolts 51 entering the upper members of the frame 1, so that the rollers 37 may be adjusted and held fixedly in adjusted positions.

By means of spring mountings 52 a suitable elastic and yieldable pressure may be exerted upon the rollers.

The bracket arms 43 and 48 are so adjusted that when the presser roller 18 is at its nearest approach to the abrading roller 22 the rollers 36 and 37 constituting guide rollers are so related to the presser roller as to permit the passage between the guide rollers and the presser roller of a skin to be treated and to hold the skin firmly yet yieldably against the presser roller, while the latter in turn holds the skin against the abrading roller with desirable pressure.

The presser roller 18 is connected up to the power receiving elements of the machine so as to be positively driven in contradistinction to being caused to rotate by the engagement of the skin therewith.

The normal tendency of the weights 16 is to cause the treadle 13 to rock the arms 10 in a direction to rotate the pinions 8 in a manner to engage the racks 7 and propel the carriage so as to move the presser roller 18 toward the abrading roller, wherefore the presser roller will hold a skin against the abrading roller with a pressure due to the weights 16.

The guide rollers 36 and 37 also engage the skin and hold it against the presser roller in a smooth, taut condition avoiding any tendency of the skin to wind upon the presser roller.

By the use of chain drive instead of the more complex transmission of the aforesaid application, not only is the construction correspondingly cheaper, but is smoother in running and far more flexible.

The use of the chain 35 for driving the presser roller 18 is particularly advantageous since the roller 18 has a range of movement toward and from the abrading roller, which movement is easily permitted by the chain 35 without stopping the con-

stant rotation of the roller 18. If toothed gearing were used for the purpose there would either be complete stoppage of the roller 18 when drawn away from the abrasive roller or the gear teeth would be so loosely connected as to be obtrusively noisy.

5 The roller 18 is covered with soft or medium hard rubber for certain work, while for other classes of work a brass presser roller is to be preferred.

10 The use of a presser roller in place of a presser plate permits the reduction of the space between the upper guide roller driven by the motion of the presser roller and the 15 fleshing point of the abrading roller. This avoids edge cutting of the skins and results in a great saving of leather. The adjustment provided for the arms 43 and 48 permits either light or hard pressure to be established on the skins between the guide 20 rollers and the presser roller. The pressure on the upper guide roller is further regulated by the spring pressure means described.

25 On occasions the lower guide roller is not needed, and then it can easily be put out of commission by moving it out of the path of the presser roller.

30 In order to provide an adjustment between the arms 10 and the treadle 13 the links 14 may include turnbuckles 53.

35 As it is necessary to frequently clean the abrading roller, a dressing tool 54 is mounted on a feed rod 55 carried by bearings 56 on the frame 1 on that side of the abrading roller remote from the presser roller. The feed rod 55 may be actuated by a roller 57 which can be moved into and out of engagement with the abrading roller by an adjusting 40 screw 58, or may be turned by hand. In either instance the tool 54 is caused to travel along the abrading roller while the latter is rotating, and thus cleansing it from matter adhering to it and deposited upon 45 the roller from the skins.

The guide rollers serve to hold the skin straight and prevent the formation of wrinkles.

50 In doubling the action of the abrading roller, or when fleshing wet skins, the movement of the rubber presser roller should be reversed.

55 The dresser for the abrading roller to keep it true and clean may be a Huntington or Diamond dresser.

What is claimed is:—

1. In a machine for treating fine tanned leather, a positively driven abrasive roller, a positively driven presser roller movable 60 toward and from the abrasive roller, means for rotating the presser roller at a slower peripheral speed than that of the abrasive roller, and an idler guide roller having a fixed mounting with relation to the abrasive 65 roller and associated with the presser roller

in operative relation thereto when the presser roller is in operative relation to the abrasive roller.

2. In a machine for treating fine tanned leather, a positively driven abrasive roller, 70 a positively driven presser roller movable toward and from the abrasive roller, and guide rollers associated with the abrasive and presser rollers arranged on opposite sides of the presser roller and provided 75 with mountings for holding the guide rollers in fixed relation to the abrasive and presser rollers during the operation of the machine.

3. In a machine for treating fine tanned leather, a positively driven abrasive roller, 80 a positively driven presser roller movable toward and from the abrasive roller, and guide rollers associated with the abrasive and presser rollers and provided with 85 mountings for holding the guide rollers in fixed relation to the abrasive and presser rollers during the operation of the machine, the mountings of the guide rollers being 90 adjustable for changing the relation of the 95 guide rollers to the other rollers, at will.

4. In a machine for treating fine tanned leather, a positively driven abrasive roller, a positively driven presser roller, a mounting for the presser roller movable with 95 relation to the abrasive roller to correspondingly move the presser roller toward or from the abrasive roller, and guide means for the leather associated with the abrasive and presser rollers and arranged on opposite sides of the presser roller, said guiding 100 means having supporting means in normally fixed relation to the abrasive roller.

5. In a machine for treating fine tanned leather, a positively driven abrasive roller, 105 a positively driven presser roller, means for driving the presser roller at a slower peripheral speed than the abrasive roller, a mounting for the presser roller movable with relation to the abrasive roller to correspondingly move the presser roller toward or from the abrasive roller, and guide means for the leather associated with the abrasive and presser rollers, said guiding means having supporting means in normally fixed 110 relation to the abrasive roller.

6. In a machine for treating fine tanned leather, a positively driven abrasive roller, a positively driven presser roller movable toward and from the abrasive roller, and 115 chain and sprocket and gearing connections between the abrasive roller and the presser roller for transmitting power from one to the other whereby the presser roller is constantly driven, the connections being proportioned to impart a slower speed of movement to the presser roller than to the abrasive roller.

7. In a machine for treating fine tanned leather, a positively driven abrasive roller, 120

- a positively driven presser roller movable toward and from the abrasive roller, and chain and sprocket and gearing connections between the abrasive roller and the presser 5 roller for transmitting power from one to the other whereby the presser roller is constantly driven, the connections being proportioned to impart a slower speed of movement to the presser roller than to the abrasive 10 roller, and said machine being provided with idler guide rollers associated with the presser roller and having mountings normally fixed with relation to the presser and abrasive rollers.
- 15 8. In a machine for treating fine tanned leather, a positively driven abrasive roller, a positively driven presser roller associated with the abrasive roller, a carriage on which the presser roller is mounted with said carriage and presser roller movable toward and from the abrasive roller, gravity means having a constant tendency to move the presser roller toward the abrasive roller, stop means for limiting the movement of the carriage 20 toward the abrasive roller, and idler guide rollers associated with and located on opposite sides of the presser roller and having mountings in normally fixed relation to the machine.
- 25 9. In a machine for treating fine tanned leather, a positively driven abrasive roller, a positively driven presser roller associated with the abrasive roller, carrying means for the presser roller having a normal constraint to move the presser roller toward the abrasive roller and having means under the control of an operator for moving the presser roller away from the abrasive roller, means for limiting the approaching movement of the presser roller toward the abrasive roller, and guide rollers 30 associated with and located on opposite sides of the presser and abrasive rollers, said guide rollers being idler rollers and having supporting means in normally fixed position upon the machine.
- 35 10. In a machine for treating fine tanned leather, an abrasive roller, a presser roller, means for positively rotating the abrasive and presser rollers at predetermined relative speeds, a carriage on which the presser roller is mounted, and means for moving the carriage and the presser roller with it toward and from the abrasive roller, comprising rack members on a fixed portion of the machine, pinion members on the carriage and meshing with the rack members, a treadle connected to the pinion members to rotate them, and overbalancing weights on the treadle to normally constrain the carriage 40 toward the abrasive roller.
- 45 11. In a machine for treating fine tanned leather, an abrasive roller, a presser roller, means for positively rotating the abrasive and presser rollers at predetermined relative speeds, a carriage on which the presser roller is mounted, and means for moving the carriage and the presser roller with it toward and from the abrasive roller, comprising rack members on a fixed portion of the machine, pinion members on the carriage and meshing with the rack members, a treadle connected to the pinion members to rotate them, and overbalancing weights on the treadle to normally constrain the carriage 50 toward the abrasive roller, the machine also having idler guide rollers associated with the abrasive and presser rollers, and supports for the idler guide rollers having adjustable connections with the fixed portion of the machine for fixedly positioning the guide rollers in chosen relations to the presser roller.
- 55 12. In a machine for treating fine tanned leather, a suitable frame, an abrasive roller mounted thereon, a presser roller having a mounting on the frame and movable with the mounting toward and from the abrasive roller, means for the application of power to the abrasive roller, direction-changing 60 gearing mounted on the frame of the machine, chain and sprocket connections between the abrasive roller and the direction-changing gearing, and chain and sprocket connections between the direction-changing 65 gearing and the presser roller.
- 70 In testimony, that I claim the foregoing as my own, I have hereto affixed my signature in the presence of two witnesses.
- 75 OTTO FELIX FEIX.
